UNITED STATES PATENT OFFICE.

CHARLES W. HAYES, OF WASHINGTON, DISTRICT OF COLUMBIA.

SHELL.

SPECIFICATION forming part of Letters Patent No. 325,538, dated September 1, 1885.

Application filed May 1, 1885. (No model.)

To all whom it may concern:

Be it known that I, CHARLES W. HAYES, of Washington, in the District of Columbia, have invented certain new and useful Improvements 5 in Projectiles; and I do hereby declare the following to be a full, clear, and exact description of the same, reference being had to the accompanying drawings, forming a part of this specification, and to the figures and letters of reference marked thereon.

This invention pertains to a new system or mode of charging and discharging explosive shells and similar projectiles; and it consists, essentially, in providing the shell or other 15 projectile with two or more compartments or receptacles, in which are contained the elements or parts of an explosive compound or mixture, and a device or mechanism for automatically liberating the said elements or parts, 20 permitting or causing the latter to mix or combine to form the explosive, said device or mechanism being preferably arranged to operate or be set in action by or during the flight of the projectile, the explosive compound or mixture thus formed to be ignited or fired by impact or percussion. By thus charging the projectile with the elements of an explosive compound, and retaining them in separate compartments or receptacles until after the 25 projectile has been fired, the liability of premature explosions is greatly diminished, and the shells can be readily charged and handled without danger to the operator, as no explosive compound other than the detonating 30 material, if such be employed, is placed or formed within the shell until the several ingredients are liberated or mingled, either by manipulation or automatically, as by the flight of the projectile.

35 A further advantage incident to the use of my said invention is the absence of danger, not only in handling, but in firing such a shell—as, for example, when the explosive compound or mixture constituting the bursting-charge 40 consists of nitro-glycerine, the elements whereof (nitric and sulphuric acids and glycerine) are non-explosive, and so long as they are uncombined can be subjected to the impact of the firing-charge without danger of exploding, 45 as would be the case were the ingredients combined before firing.

For the purpose merely of illustrating the manner of applying and using my said invention, I have shown in the accompanying drawings a form of shell designed to accomplish 55 my said purpose; but I wish it distinctly understood that the form, preparation, and relative arrangement of the parts can be changed and modified at will without departing from the spirit of my said invention, so long as the 60 principle and mode of operation as herein set forth are retained.

In said drawings, Figure 1 is a longitudinal sectional view of a shell, illustrating one mode of applying my invention; and Figs. 2 and 3 65 are similar views of modifications.

Similar letters of reference in the several figures indicate like parts.

The letter A indicates a shell, of iron or other suitable material, made hollow, and, for 70 convenience in charging, in two or more sections, a' a''. The interior of the shell A is divided into two or more compartments, A' 75 A'', lined with a suitable non-corrosive material, or provided with separate receptacles (shown in dotted lines) composed of a material that will not be acted upon by the element which it is designed to retain.

In the illustrations given the explosive to be formed is nitro-glycerine, and the compartment 80 A', Figs. 1 and 2, is designed to contain the nitric and sulphuric acids, combined in proper proportion, and the compartment A'' the glycerine; or one acid may be charged in the compartment A' and the other in the compartment 85 A'', while the glycerine is charged in the mixing-chamber A''.

The compartments A' A'' are formed or provided with passages a³, communicating with the mixing-chamber A'', said passages being 90 closed and sealed by suitable stoppers, the removal of which will permit the material to combine or flow into the mixing-chamber A''.

As shown, the stoppers a⁴ are arranged to be actuated or withdrawn from the passages a³ 95 by longitudinal threaded spindle B acting upon a threaded nut, B', which latter is connected to the stoppers by a cross-piece, b, or levers b', Figs. 1 and 2; or said nut may itself form part of the stoppers, as shown at B', Fig. 3.

The spindle B is protected by a suitable covering or coating to prevent the acid from

- attacking it; or it may be passed through a sleeve, b^2 , Figs. 1 and 2, forming part of the division-wall between the two compartments A' and A^2 . The rotation of the spindle effects the withdrawal of the stoppers a' and permits the contents of the chambers or receptacles A' and A^2 to mingle in the chamber A^3 , where they are thoroughly mixed, this operation being facilitated by the action of the stirrers c , applied to the spindle, if desired, and in order that the stoppers may be automatically withdrawn during the flight of the projectile, and not before, (unless manipulated for that purpose,) the spindle is continued beyond the point of the projectile, and provided with a device—such as the propeller C —which will be set in operation by the resistance encountered through the atmosphere. The propeller-blades may be constructed separate from the spindle, and with a screw-threaded extension fitting into the end thereof, so that they may be removed, and thus lessen the liability of the spindles being revolved and the materials mixed before the projectile is fired from the gun. In this way the flight of the projectile is caused to inaugurate the formation of the explosive by opening the passages and permitting or effecting the mixture of the ingredients contained within the shell.
- The shell shown in Fig. 2 is formed in two compartments, A' and A^2 , each containing one or more of the materials which go to make up the explosive compound, the admixture being accomplished in the rear chamber, A^3 .
- If nitro-glycerine is the explosive to be formed, it may be fired by any of the known means for exploding such material by the impact of the projectile against the object fired at. When the spindle B is employed for effecting the admixture of the elements, it may be sustained in position by a collar, b^3 , which, when the end of the spindle meets a sufficient resistance, will be broken or displaced, thereby permitting the inner end of the spindle to be brought violently into contact with the interior surface of the shell and explode the charge, a suitable detonator, D , being located within the shell in proximity to the end of the spindle, if desired.
- I claim as my invention—
1. The combination, in a shell or projectile such as described, of separate compartments or receptacles containing the elements of an explosive compound, and a spindle for liberating the contents of the said receptacles and permitting them to mingle, said spindle extending outside the body of the shell and carrying a stirring or mixing device, substantially as described.
  2. In combination with a shell provided with

receptacles or compartments charged with the elements of an explosive compound, as described, a spindle for releasing the contents of said receptacles, and a detonator arranged for co-operation with said spindle, substantially as described.

3. In combination with the shell provided with compartments or receptacles containing the elements of an explosive compound, the spindle for releasing the contents of the said compartments or receptacles, provided with the removable propeller located outside the body of the shell, substantially as described.

4. A shell or similar projectile formed with separate compartments or receptacles to contain the elements of an explosive mixture or compound, and provided with communicating passages extending through the walls of the chambers, valves or stoppers for closing said passages, and devices, substantially such as indicated, for operating said valves or stoppers from the exterior of the shell, substantially as and for the purposes set forth.

5. The combination, with a shell or similar projectile provided with separate compartments for the elements of the explosive mixture, and passages leading from said compartments to a mixing-chamber, of valves for closing said passages, and a device—such as a spindle—extending through the wall of the shell, and devices for connecting said spindle to said valves for simultaneously opening the passages and permitting the elements contained therein to mingle, substantially as described.

6. The combination, with a shell formed with separate compartments or receptacles with communicating passages, of valves or stoppers for closing said passages, a spindle connected to said valves, and provided with devices exterior to the shell for actuating said spindle, whereby the contents of the chambers or receptacles are released and caused to mingle, substantially as described.

7. The combination, with a shell having separate compartments or receptacles containing the elements of an explosive compound, of a pneumatic device or motor located in advance or upon the forward end of the shell, and a spindle connected to said motor and operating to release the elements of the explosive contained within the shell, whereby the mixture or mingling of the said elements is effected by the pressure produced upon the atmosphere by and during the flight of the projectile, substantially as described.

CHARLES W. HAYES.
